UNITED STATES PATENT OFFICE.

WILLIAM H. WINSLOW, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 27,348, dated July 13, 1897.

Application filed June 15, 1897. Serial No. 640,926. Term of patent 14 years.

To all whom it may concern:

Be it known that I, WILLIAM H. WINSLOW, a citizen of the United States, residing at Chicago, in the county of Cook and State of Illinois, have invented and produced a certain new and useful Design for Prism-Plates, of which the following is a description.

My invention relates to a design for prism-plates, and is illustrated in the accompanying drawing, wherein is shown an elevation of a prism-plate containing my invention.

A A are hexagon-shaped prism-lights; B B, surrounding frame or border pieces; C C, opaque strips between the prism-lights; D D, prisms on the prism-lights; E, enlarged opaque corner-pieces between the prism-

lights at their corners, said corners being cut away, as indicated.

The essential features of my design are found in a prism-plate composed of a series 20 of hexagon prism-lights, each having its corners cut off, and opaque framing-strips between the lights and opaque enlargements between the corners of the lights.

I claim—

The design for a prism-plate substantially as shown and described.

WILLIAM H. WINSLOW.
